FENCE WIRE RETAINING INSULATING DEVICE
Jack F. Adamson, Eyota, Minn.
Filed April 23, 1959, Ser. No. 808,516
1 Claim. (Cl. 174—158)

This invention relates to a retainer in connection with a fence post for supporting a strand of fence wire particularly adapted for use in connection with forming an electrically charged fence.

It is desirable to have such a device for mounting on fence posts wherein all of such devices to be used may be mounted in one operation and the fence wire to be retained therein be laid out along the line of said posts and then very readily be positioned to be supported and retained in said devices in one continuous operation. Many devices commonly used, such as porcelain insulators have coupling portions and these require that the wire be secured independently to each device as with a nail or a screw, or that there be sufficient slack in the wire so that portions of the wire may be turned at an angle to the direction of the wire so that said portions can be slipped into clips or rings. It is desirable to have such a device wherein the wire may be in a taut condition and be placed directly into the retainers without any bending or twisting of the wire and whereby the wire may be removed from any single retaining device for replacement of the retainer without interference such as would be caused by a need for loosening the wire as a whole.

It is an object of this invention therefore to provide a device comprising a support and retainer for an electrically charged fence wire wherein said device has an open-ended portion into which a wire extending in a direction at right angles to the plane of the retainer may be placed directly into the retainer without any twisting, bending or angling thereof with a closure member adapted to be readily positioned for retaining the wire therein.

It is another object of this invention to provide a device adapted to be readily secured to a fence post and having an open-ended substantially U-shaped insulated portion in substantially a vertical plane into which a wire extending in a direction at right angles to said plane may be moved directly thereto by simply being raised to the level of the device with a closure member in connection with said device for readily retaining said wire therein.

It is a more specific object of this invention to provide a device and method for forming the same for supporting and retaining therein a fence wire for forming an electric fence, said device comprising a length of suitable wire being reversely bent to form a closed end portion and spaced sides, said closed end portion being reversely bent to form an open-ended U-shaped portion having its sides formed of doubled portions of said wire and having aligned loops formed at the free ends of said U-shaped portion whereby a strand of wire may be positioned in said device by being moved directly thereto, and a closure member adapted to be disposed through said loops for retaining said wire.

These and other objects and advantages of the invention will be fully set forth in the following description made in connection with the accompanying drawings in which like reference characters refer to similar parts throughout the several views and in which:

FIG. 1 is a fragmentary view in elevation on a reduced scale showing applicant's device in operating position and a portion thereof in dotted line in inoperative position;

FIG. 2 is a view on an enlarged scale partially in vertical section and partially in side elevation taken on line 2—2 of FIG. 1 as indicated by the arrows, with a

2

portion thereof shown in alternate position in dotted lines;

FIG. 3 is a top plan view of the view shown in FIG. 2;

FIG. 4 is a fragmentary view in plan taken on line

5 4—4 of FIG. 2 as indicated by the arrows;

FIG. 5 is a view in side elevation similar to FIG. 2 showing a modification of a portion thereof;

FIG. 6 is a view similar to FIG. 5 showing a portion thereof in different positions; and

10 FIG. 7 is a view in perspective on an enlarged scale showing a portion of a fence post and a modification of applicant's device mounted thereon in operating position.

With reference to the drawing, like reference characters will be used to indicate identical parts throughout the 15 several views. Referring to FIG. 1, applicant's device 10 is shown generally on a reduced scale in operating position on fence posts 11 and having supported and retained therein a fence wire 12. Said wire will be adapted to conduct an electrical current in forming an electrical fence. Said wire 12 is shown in dotted line as 12' to indicate its position on the ground prior to being placed in operating position.

With reference to FIGS. 2—4, one form of applicant's 25 device is shown wherein applicant's device 10 comprises a length of wire 14 of suitable dimension and rigidity.

Said wire 14 will be reversely bent to form a closed end portion 14a and have parallel sides 14b and 14c. Said closed end portion is reversely bent to form an open-ended U-shaped portion 14d with loops 14e and 14f formed at the free ends of said U-shaped portion 14d. Said sides 14b and 14c are here shown to be parallel and are indicated as being disposed in a common vertical plane. The free end portions 14g and 14h of said wire 14 will be bent in the plane of said sides in directions away from one another. Loops 14k and 14m will be formed in the free ends of said portions 14g and 14h. Disposed through said loops 14k and 14m are fastening means 16 here indicated as being in the form of nails. The open-ended U-shaped portion 14d and the portions 30 of the sides 14b and 14c adjacent thereto will be coated with an insulating material 14w, such as of a rubber or plastic material, which may be formed on said wire 14 by a dipping or spraying process.

Pivotedly secured to the loop 14e is a closure member 17 comprising a reversely bent length of wire having an elongated loop 17a formed therein and having its lower end portion 17b secured together to close said loop and form a stem which is here indicated as having been formed by twisting together the free ends of said member 17. Said loop 17a will be of sufficient length to permit the stem portion 17b to be raised above and disposed through the loop 14f.

In operation, when it is desired to install a length of fence wire 12 for forming an electrical fence, and after 55 the posts 11 have been installed, applicant's supporting and retaining device 10 will be secured in operating position on each of said posts by a suitable fastening means. The wire 12 will be strung along at the foot of the posts 11 and may be stretched tight at this time. All that is required of the operator then is to quickly lift the wire into the open-ended U-shaped portions 14d with the closure member 17 having been readily held out of the way. Said closure member is quickly placed in operating position by simply lifting the stem portion 17b and dropping it through the loop 14f.

With reference to FIGS. 5 and 6, a modification of the closure portion 17 of applicant's device is shown. In place of the closure member 17 having an elongated loop and stem portion, a closure member 20 is indicated formed of a suitable length of wire having a coating 21 of insulating material thereon and being reversely bent to have adjacent side by side portions forming a stem portion

20a. The lower ends 20b of said side by side portions are shown extending below the insulating material 21 and are here reversely bent to form closed loops. The upper closed end portion of said member 20 is extended through the loop 14e and reversely bent therethrough to form a loop 20c in pivotal engagement with said loop 14e. Said member 20 is easily pivoted in a swinging movement as indicated in dotted line in FIG. 6. The lower portion of said member 20 is moved between the lower side of said U-shaped portion 14d and the side portion 14c and is moved forwardly therebetween to be disposed or positioned in the loop 14f in its closure position. Said member 20 is easily moved to an out-of-the-way position, as is indicated in FIGS. 5 and 6, for the placement of the wire 12 into said portion 14d or for removal therefrom.

A further modification of the applicant's device is indicated in FIG. 7 in which a supporting and retaining member 25 is indicated comprising a length of wire 26. Said strand of wire 26 is formed by being reversely bent to have a closed end portion 26a and spaced parallel sides 26b and 26c. Said closed end portion is reversely bent to form an open-ended U-shaped portion 26d having loops 26e and 26f formed at its free ends. Said U-shaped portion 26d and the portions of sides 26b and 26c adjacent thereto will be coated, as by spraying or dipping with a suitable insulating material 27. The free ends 26g and 26h to the rear of the U-shaped portion 26d of the wire 26 are bent at angles away from one another in the plane of said U-shaped portion 26d. Said bent portions 26g and 26h have their free ends 26k and 26m bent to be in a vertical plane. Applicant's device 25 is here shown secured onto a plate member 29 indicated as being formed of an elongated strip of sheet material having a flat central portion 29a with transversely extending band portions 29b and 29c at either end of said central portion and reversely bent to overlie and hold secure the portions 26k and 26m of said member 25. The outer end portions of said member 29 are reversely bent to form loops 29o and 29p and also are provided with apertures 29r.

Indicated in FIG. 7 is an angular post 32. Said member 29 is shown secured to said post 32 by wires 34 extending through said loops 29o and 29p and being wound about said post 32.

A right-angled pin 36 is disposed through said loops 26e and 26f to form a closure member. Said member 36 is here shown formed having a short angled head portion 36a and an elongated depending leg portion 36b with said portion 36b being disposed through said loops 26e and 26f. Said pin 36 will be coated with said insulating material 27.

In operation, applicant's device 25 will be secured to a post 32 by suitable means, as by the use of wires 34 extending through the loops 29o and 29p. Said device 25 will be secured to each post along the line of the fence. The fencing wire 12 will be strung out along the line of said posts and may be pulled taut if desired and be all set up for operation except for being placed in the retainers 25. No slack is required in the wire for this purpose. The wire 12 is then raised and simply disposed in the insulated open-ended U-shaped portions 26d, and the pins 36 are dropped in closing position through the loops 26e and 26f to enclose the open end of said portion 26d. Thus

wire 12 is very quickly and efficiently mounted in its final operating position.

The essential advantages present in the applicant's supporting and retaining members are that all of these retainers can be mounted along the line of a fence, and the wire to be electrified can be strung out along the line of the fence and be tightened in position. No slack is required in the wire for mounting it in applicant's members. The wire is simply raised and moved into the retaining portion of applicant's members and then is locked therein very readily, as indicated above. If any post is damaged or if any retainer is broken, a replacement may be made very readily without disturbing the rest of the fence. The wire need not be loosened to remove or replace a post or one of applicant's devices. No slack is necessary in the wire 12 to remove the same from a retaining member. This is a substantial advantage in the use of the applicant's device.

Thus it will be seen that I have provided a very simply made supporting and retaining member for a wire to be electrified in forming an electric fence.

It will of course be understood that various changes may be made in the form, details, arrangement and proportions of the device and in the steps and sequence of steps of the method without departing from the scope of applicant's invention, which, generally stated, consists in a method and device capable of carrying out the objects above set forth, such as disclosed and defined in the appended claim.

What is claimed is:

In connection with a fence wire to be charged with electricity and a post for forming an electric fence, a retainer for said fence wire comprising a length of wire reversely bent to have spaced parallel sides having a closed end portion at one end portion of said retainer and free end portions at the other end portion of said retainer, said closed end portion and adjacent parallel side portions being reversely bent to form a U-shaped portion having an open outer end, vertically aligned loops formed at the outer ends of said reversely bent parallel side portions with said parallel sides and the legs of said U-shaped portion being closely adjacent one another, an elongated plate member, said parallel sides of said wire at the other end portion of said retainer being secured to said plate member, means in connection with said plate member for fastening the same to said post, a closure member removably disposed through said aligned loops, and an insulating coating about said retainer.
